SHEET FOLDING MACHINE

Gustave S. Berman, New York, N. Y.

Application March 16, 1946, Serial No. 654,857

7 Claims. (Cl. 93—1)

1

This invention relates to a sheet folding machine, and more particularly to a machine for folding pliable sheet materials such as blanks of paper, paper-board, fibre, or plastic, to form the shields or covers of umbrellas and parasols.

The principal objects of this invention are to manufacture umbrella and parasol shields quickly, efficiently and cheaply.

Another object is a machine for rapidly and effectively pleating blanks of sheet material, thus converting them without spoilage into umbrella and parasol shields.

Other objects will appear from the detailed description which follows.

In accordance with this invention the stock cut in the form of a centrally holed circular sheet or shield blank is centered and then clamped between the upper and lower members of a forming die by which the blank is manipulated against the radially corrugated surface of a conical male die element, is then pressed against said corrugated surface under substantial pressure, in the presence where necessary, of applied heat, until the blank is effectively pleated to form a shield, which is then released and removed from the corrugated surface of the male die.

In the drawings comprising six sheets of seven figures numbered Figs. 1 to 7 inclusive, one suggested embodiment of the invention is illustrated.

Fig. 1 is a front view of a press embodying the invention.

Fig. 2 is a side view of the press of Fig. 1;

Fig. 3 is a plan view of the die mechanism;

Fig. 4 is a side view partly in section showing the die mechanism open with the blank in feeding position;

Fig. 5 is a side view partly in section showing the blank clamped between the die members;

Fig. 6 is a side view partly in cross section showing the relative positions of the several parts of the die mechanism after the blank has been effectively pleated to form the shield; and

Fig. 7 is a horizontal sectional view of a fragment of the forming die only taken along the line 7—7 of Fig. 6 looking in the direction of the arrows.

Like reference characters designate corresponding parts throughout the several figures of the drawings.

For convenience in understanding the invention and its mode of operation, the die mechanism which includes the upper die 50, the lower die 60 and the forming die 70 (Figs. 1 and 2), will be described separately from the operating mechanism therefor. A manually controlled

power press 10 may be used for operating the die.

The power press 10 may be hydraulically operated. It may consist of a suitable frame 11 supporting a cylinder 12 mounted thereon in any suitable manner. A piston 13 mounted for sliding movement within the cylinder 12, is mechanically coupled to a ram 14 adapted to rise and fall with the piston 13. The ram 14 is made of tubular construction to receive a rod 47, which is mounted for axial telescopic movement relative to the ram. The piston 13 may also be made hollow to receive the upper end of rod 47.

To effect the telescopic action the ram 14 is provided with a slotted keyway 48 (Fig. 6) for receiving the stud 49 of the rod 47. The limits of the telescopic action between the ram 14 and the rod 47 are determined by the length and position of the slotted keyway 48 and the location of the stud 49.

20 The rod 47 protrudes beyond the lower end of ram 14 for a substantial distance. At its lower extremity the rod 47 carries a collar 53 forming the lower hub of the upper die 50. A collar 57 which is mounted for axial sliding movement upon the rod 47, constitutes the upper hub of the upper die 50. A coiled spring 58 is mounted upon the rod 47 between the upper hub 57 and an adjustable collar 92 which is locked in position by the set screw 93. Spring 58 normally tends to separate the hubs 57 and 53, to retain the triangular shaped irons 51 carried by the links 55 in a horizontal position, substantially as shown in Figs. 1, 2, 4 and 5.

35 The piston 13 is hydraulically actuated under control of a four-way valve 15 which is connected to the opposite ends of the chamber of the cylinder 12 by means of feed pipes 16 and 17, and to the hydraulic system by means of the sump pipe 18 and pressure pipe 19.

40 The four-way valve 15 may be of any conventional type. In one position of the valve, the pressure pipe 19 is connected with the feed pipe 17, and the sump pipe 18 with the feed pipe 16, while in the other position of the valve the connections are reversed thus connecting the pressure pipe 19 with the feed pipe 16, and the sump pipe 18 with the feed pipe 17. The four-way valve 15 may be either a rotary or a slide valve. As shown in the drawings the valve 15 45 is provided with a slide valve 26 adapted to be operated by a link and lever system under control of the foot pedal 40, as hereinafter more fully described.

The hydraulic system for actuating the piston 50 includes a sump tank 25 containing a suit-

able fluid 44 located in the sump 24 in the base of the frame 11. The hydraulic pump 22 draws the fluid 44 from the sump tank 25 by way of supply pipe 23, and pumps the fluid under pressure into pressure pipe 19. The pump 22 may be coupled to any suitable prime mover such as the electric motor 46 (Fig. 1).

The hydraulic system may be provided with a suitable pressure gauge 20 connected to the delivery side of the pump 22 under control of a suitable shut-off valve 21.

One end of a treadle 41 is pivotally mounted at 42 to a post 43 while the opposite end terminates in a pedal 40. The treadle 41 is provided with a suitable system of levers for operating the slide valve 26 of the four-way valve 15. This lever system may consist of a connecting rod 37 interconnecting the treadle 41 and the lever arm 33, and another connecting rod 31 interconnecting the lever arm 33 and the lever arm 27 which controls the operation of the slide valve 26 of the four-way valve 15.

The lever arms 27 and 33 are pivotally mounted at 28 and 34 respectively to the frame 11 of the press 10. The pins 35 and 39 connect the upper and lower holed heads 36 and 38 of connecting rod 37 to the lever arm 33 and treadle 41 respectively. The connecting rod 31 which forms a link between the lever arms 27 and 33 is slidably supported in the holed brackets 30 and 32 which form a part of the press frame 11. A suitable coiled spring 88 controls the return to normal movement of the system of levers including connecting rod 31. The tension of spring 88 is controlled by an adjustable collar 86 which can be locked upon the rod 31 by a set screw 87.

The throw of the lever arms 27 and 33 and of the treadle 41 may be regulated in any suitable manner as by means of a split collar 29 adjustably mounted upon the connecting rod 31, and by the lower holed head 38 which is threaded upon the connecting rod 31 to facilitate changes of rod length.

The amount of pressure generated by the pump 22 will depend among other things upon the capacity of the pump and the speed of rotation of the electric motor 46. The link and lever system is so arranged with respect to the four-way valve 15, that when foot pressure is applied to the pedal 40 of treadle 41 pressure pipe 19 is connected to feed pipe 16 to drive piston 13 to the lower end of cylinder 12 causing the ram 14 to descend; and when foot pressure is removed from the pedal 40 the pressure pipe 19 is connected to the feed pipe 17 forcing the piston 13 upwards in the cylinder 12 thus raising the ram 14.

The die mechanism includes the upper die 50, the lower die 60 and the conical male die 70.

The upper die 50, includes a series of radially projecting pressing irons 51. Each pressing iron 51 is a triangular pyramid having its apex pivotally connected at 52 to the lower hub 53. Each pyramidal pressing iron 51 also conforms in vertical cross section to an inverted triangle, to permit its inverted V shaped lateral faces 89 and 90 to seat against the lateral faces 72 and 73 constituting one of the tapered corrugations of the star shaped conical male die 70.

Each pressing iron 51 is also supported by an angular link 55, which has one end pivotally connected at 54, to the pressing iron 51, and its other end pivotally connected at 56 to the upper hub 57. The hub 57 is axially slidable along the

rod 47 to swing the pressing irons 51—51 in unison about the lower hub 53 to simulate the general mechanical movement of the rib-stays of an umbrella. The spring 58 tends to separate the hubs 53 and 57, and normally tends to retain the pressing irons 51—51 in a horizontal position substantially as shown in Fig. 4. The tension of spring 58 is regulated by means of an adjustable collar 92 which is locked by a set screw 93. When the hub 57 is moved axially upon the rod 47 towards the hub 53, the links 55—55 move about their pivotal connections 56 and 54 to force the pressing irons 51—51 outwards towards the shaft 67 of the male die 70 until their lateral faces 89—90 register with the lateral faces 72—73 which form the fluted corrugations of the star shaped male die 70.

The lower die 60 consists of a series of radially disposed carrying and forming arms 61, each pivotally connected at 62 to the head of the shaft 67. The upper face of each arm 61 is bevelled to form a peak or apex 91. A series of links 64—64 are pivotally connected at 63—63 to the carrier arms 61—61 and at 65—65 to a hub 66 which is mounted upon the shaft 67 for axial sliding movement relative thereto. A spiral spring 68 is mounted upon the shaft 67 and normally tends to force the hub 66 upwards towards the head of the shaft 67, thus normally maintaining the carrier arms 61 in a horizontal (open) position substantially as shown in Fig. 4.

The forming die 70 is a radially fluted cone. The flutings consist of a series of pairs of re-entrant lateral faces 72—73 defining ridges with V-shaped valleys 74 therebetween forming a star shaped cone. A series of vertically disposed slots 71—71 are formed in the ridges of the cone, to afford free passage for the carrier arms 61—61. The clearance between the carrier arms 61—61 and the walls of the slots 71—71 is such that the arms 61—61 substantially close their respective slots 71 so that their respective peaks 91 form the ridges of the star shaped cone.

The male die 70 may be anchored to a base plate 76 by means of dowel pins 77. The base plate 76 is adapted to be anchored to the working table 45 of the press 10 in any suitable manner as by means of the bolts 75—75 passing through the ears 83—83. The male die 70 is star shaped in horizontal cross section, the lateral faces 72 and 73 between the points of the star defining a reentrant angle forming a V shaped fluting having a vertex 74. Each pair of lateral faces 72 and 73 and their vertex 74 in conjunction, form a seat for the lateral faces 89 and 90 of one of the triangular pyramidal pressing irons 51 of the upper die 50. Each ridge formed by the merger of adjacent lateral faces 72 and 73 is slotted at 71 to afford free passage for one of the carrier arms 61 and its associated link 64 of the lower die 60. The apex of the conical male die 70 is provided with an opening adapted to receive the upper end of the shaft 67, which is suitably finished off as by beveling to form a centering device 69 for receiving the opening in the center of the shield blank 80, whereby the blank 80 may be placed in correct registry with the die mechanism preparatory to initiating the pleating operation. The height of the shaft 67 with respect to the conical die 70 may be regulated by means of the collar 81 and its set screw 82.

Suitable heating elements 84 may be located within the forming die 70 for heating the die to increase its pressing efficiency. The heating elements 84 may be of any preferred type such as

electrically heated resistance coils, gas burners, or super heated steam coils, or the like.

Principle of operation

The die mechanism 50, 60 and 70 having been properly installed in the press 10, a shield blank 80 of the desired pliable sheet material is inserted between the upper die 50 and the lower die 60 so that the central opening in the blank 80 registers with the centering device 69 of male forming die 70. The blank 80 is supported upon the carrier arms 61 of lower die 60, substantially as shown in Fig. 4 of the drawings.

When the operator applies foot pressure to the pedal 40 the treadle is depressed and actuates the slide valve 26 through the system of levers including the lever arms 33 and 27 and the connecting rods 37 and 31. The slide valve 26 moves into position to connect the pressure pipe 19 to the feed pipe 16, and the feed pipe 17 to the sump pipe 18.

The hydraulic pressure applied to the chamber 12 forces the piston 13 and ram 14 to descend. The ram 14 in descending moves the shaft 47 and upper die 50 downwards until the lower hub 53 of shaft 47 registers with the cone shaped head of the centering device 69 of the shaft 67, which arrests the further downward movement of the rod 47. The lateral faces 89 and 90 of the pressing irons 51 engage the surface of the blank 80, so that the blank is now securely held between the forming ridges 91 of the carrier arms 61 of lower die 60 and the pressing irons 51 of upper die 50, substantially as shown in Fig. 5.

The continued descent of the piston 13 and of the ram 14, causes the stud 49 of the rod 47 to rise in the slotted keyway 48 of ram 14, thus telescoping the ram 14 upon the rod 47 and sliding the upper hub 57 of upper die 50 axially downwards upon the rod 47 against the increased tension of the coiled spring 58.

The downward movement of the hub 57 causes the links 55-55 to turn upon the pivotal connections 56-56 of hub 57 and upon the pivotal connections 54-54 of the pressing irons 51-51, thus turning the pressing irons 51-51 about the pivotal connections 52-52 of the lower hub 53, and causing the pressing irons to swing downwards as indicated generally in Fig. 6.

The downward swinging movement of the pressing irons 51-51 of upper die 50 applies increased pressure to the surface of the blank 80. This pressure is transmitted by the blank 80 to the carriers 61-61 which swing about their pivotal connections 62-62 thus forcing their associated links 64-64 to move the hub 66 downwards upon the shaft 67 against the increasing tension of the coiled spring 68. The coiled spring 68 is a relatively lightly tensioned spring, and will yield to the force exerted by the pressing irons 51-51 through the blank 80, thus preventing the ridges 91 of the carrier arms 61 from injuring the sheet material of which the blank 80 is made.

The carrier arms 61 continue to swing downwards towards the shaft 67 through the slots 71-71 in the ridges or vertices of the star shaped male die 70 until the lateral faces 89 and 90 of the pressing irons 51-51 force the sheet material of the blank 80 into the fluted valleys 74-74 and against the forming ridges 91 of the carrier arms 61 which now form a continuation of the lateral faces 72-73 of the star shaped male die 70, substantially as shown in Fig. 6 of the drawings.

The pressure exerted upon the blank 80 by the lateral faces 89 and 90 of the pressing irons 51-51 acting against the lateral faces 72 and 73 of the male die, effect a pleating action upon the blank 80 which is permanently creased radially along the lines delineated by the forming ridges 91 which now in effect form a part of the male die 70 and reversely permanently creased radially along the lines delineated by the inverted ridges formed by the lateral faces 89 and 90 of the pressing irons 51-51.

When foot pressure is removed from the pedal 40 the slide valve 26 is moved into position to connect pressure pipe 19 with feed pipe 17 and to bleed feed pipe 16 over sump pipe 18 to sump tank 25. Piston 13 now moves upwards expelling the fluid 44 from the upper end of chamber 12 by way of feed pipe 16 and sump pipe 18 to sump tank 25.

The upward axial movement of piston 13 and ram 14 relative to the rod 47 releases the coiled spring 58 which in turn forces the upper hub 57 of upper die 50 away from its lower hub 53. The upward axial movement of upper hub 57 draws the links 55-55 upwards, thus causing the pressing irons 51-51 to swing upwards and disengage the blank 80. As the pressing irons 51-51 disengage the blank 80 the coiled spring 68 of lower die 60 forces the hub 66 upwards along the shaft 67 thus causing the links 64-64 to restore the carrying arms 61-61 to their normal position. The upward movement of the carrying arms 61-61 lifts the pleated blank 80 off the male die 70.

The ram 14 continues its upward movement until the stud 49 reaches the bottom of the keyway 48, whereupon the continued upward movement of the piston 13 and ram 14 disengages the shaft 47 from the shaft 67 and the die mechanism ultimately returns to the normal position substantially as shown in Fig. 4 of the drawings. The completed blank 80 disengages the centering device 69 and may be removed from the press.

A new blank 80 may now be inserted between the upper and lower dies 50 and 60 in correct registry with the centering device 69, and the cycle of operations repeated.

What is claimed is:

1. A die for a sheet folding machine including a ridged and fluted cone comprising a star shaped member, each ridge having a slot formed therein extending from the ridge peak radially inwards towards the center of the cone, carrying and forming arms mounted to swing in said slots, a support, and a series of pressing irons carried by said support and operable relative thereto to engage the fluted surface of the cone.

2. A sheet folding machine including a die therefore, said die comprising a star shaped cone, means adapted to effect correct registry between a sheet and said cone, said cone having a series of radially spaced pairs of laterally reentrant substantially triangular faces defining ridges and flutings, each of said ridges having a vertically disposed slot formed therein and extending from the apex towards the base of the cone, means slidably mounted in said slots for yieldably supporting a sheet in folding position, a shaft mounted for axial movement towards and away from the cone, a series of pressing irons seatable in the flutings of said cone, and means for pivotally supporting the pressing irons upon the shaft to effect simultaneous movement thereof 75 into and out of registry with said flutings.

3. In an umbrella shield folding machine, a conical die member, means adapted to effect correct registry between a shield blank and said die, said cone having a series of regularly spaced pairs of laterally reentrant substantially triangular faces defining flutings with ridges therebetween, each of the said ridges having a vertically disposed slot formed therein and extending from the apex towards the base of the cone, a series of fold-defining arms registering with said slots for yieldably supporting a shield blank in position preparatory to folding, a shaft mounted for axial movement towards and away from the die, a series of pressing irons seatable in the flutings of said die, said pressing irons being pivotally supported upon said shaft for simultaneous movement into and out of registry with said flutings, and means for imparting axial movement to said shaft and for seating said pressing irons in said flutings to effect pleating of a shield blank clamped therebetween to produce a pleated umbrella shield.

4. A die member for a sheet folding machine comprising a cone shaped die member, means adapted to effect correct registry between a sheet and said die member, a series of regularly spaced pairs of laterally reentrant substantially triangular faces formed in the surface of said cone to define a corrugated seat for a second and complementary die member, a shaft mounted in co-axial alignment with said cone, a complementary die member comprising a series of pressing irons spaced to register with said corrugated seat, said pressing irons being pivotally supported on said shaft for movement into and out of registry with said seat, and means for effecting simultaneous movement of said pressing irons relative to said corrugated seat.

5. A die for a sheet folding machine comprising a cone shaped die member, means adapted to effect correct registry between a sheet and said die member, a series of regularly spaced pairs of laterally reentrant substantially triangular faces formed in the surface of said cone defining flutings with ridges therebetween, each of said ridges having a slot formed therein extending along the peak of the ridge radially inwards towards the center of the cone, a shaft mounted in co-axial alignment with said cone, a series of sheet-carrier arms one for each of said slots, each carrier arm having its upper edge face bevelled to form the peak of one of the ridges of said cone, said carrier arms being pivotally mounted upon said shaft in alignment with said slots, and said carrier arms

5 being yieldable about said pivots when folding pressure is applied to a sheet supported upon said arms to bring their upper edge face bevels into position to form the peaks of said ridges during sheet folding operation.

10 6. A die for a sheet folding machine comprising a conical male die member, the apex of the conical male die-member being adapted to center a sheet in position to be folded by said die, said male die-member having a series of regularly spaced pairs of laterally reentrant substantially triangular faces defining flutings with ridges therebetween, a shaft supported above the apex of said die member, a second die member comprising a series of pressing irons supported by said shaft and pivotally movable relative thereto to engage the flutings in said male die, and means 15 slidably operable along said shaft to simultaneously move said pressing irons into and out of engagement with said flutings and ridges.

20 7. In a sheet folding machine, a conical die-member, means adapted to effect correct registry between a sheet and said die, said cone having a series of regularly spaced pairs of laterally reentrant substantially triangular faces defining flutings with ridges therebetween, a shaft positioned above and co-axially movable towards and away from the conical die-member, another die-member comprising a series of pressing irons seatable in the flutings of said conical die-member, a hub mounted to slide along said shaft, said pressing irons being pivotally connected to said hub and movable relative to said shaft into registry with said flutings, means for imparting movement to said hub to simultaneously register all of said pressing irons with said flutings to accomplish the pleating of a blank when positioned therebetween, and means for heating the conical die-member.

40 GUSTAVE S. BERMAN.
